GAS ANCHOR

Kork Kelley, Wichita Falls, Tex.

Application April 8, 1940, Serial No. 328,561

1 Claim. (C.I. 103—40)

This invention relates to new and useful improvements in gas anchors and flowing devices particularly adapted for use in conjunction with the production of oil wells.

One object of this invention is to provide a gas anchor of a single-cycle type which anchor may be used either with or without the usual pump assembly.

Another object of this invention is to provide a gas anchor or flowing device which device is operated by the weight of the fluid column.

Another object of this invention is to provide means for positively prohibiting the entrance of gas into the fluid column.

A still further object of this invention is to provide an auxiliary valve within the main valve whereby it is impossible to center the device.

Another object of this invention is to provide valve means within the body of the device to permit the escape of undesirable gases.

A still further object of this invention is to provide means whereby a portion of the device contains fluid ready to be lifted at all times.

A still further object of the invention is to provide a float control so arranged as to be used either with the open side of said float facing upwardly or said open side facing downwardly and still maintaining the same efficiency in operation.

A construction designed to carry out the invention will be hereinafter described together with other features of the invention.

The invention will be more readily understood from a reading of the following specification and by reference to the accompanying drawing, in which an example of the invention is shown, and wherein:

Figure 1 is a view partly in elevation and partly in section showing a gas anchor or flow valve constructed in accordance with the present invention and showing the relative parts in their closed positions.

Figure 2 is a view similar to Figure 1 showing the relative parts of the device in their open positions.

Figure 3 is a horizontal cross-sectional view taken on the line 3—3 of Figure 2.

Figure 4 is a view partly in elevation and partly in section of a slightly modified form of this invention and showing the valve members in their intermediate positions.

In the drawing, the numeral 10 designates the usual standing valve collar disposed on the extreme lower end of the working barrel 11. The body 12 of the gas anchor is comprised of an

elongated cylindrical housing 13 having perforations 14 provided therein and being closed at both its upper and lower ends by swedged nipples 15 and 16 respectively. The lower nipple 16 is closed by a plug member 17 whereby a sand trap is formed.

The upper nipple 15 is provided with an integral internal bushing 15' whereby a chamber A is formed within the upper end of the nipple which chamber is closed at its upper end by the standing valve. A check valve 16a is provided in the upper nipple 15 communicating with the chamber A and terminating outside of said chamber within the well casing (not shown). The purpose of this check valve is to provide means for draining the tubing when it is desired to pull the standing valve for any of the various reasons. Thus, the operator is able to pull a "dry string."

20 A length of tubing 18 is threaded into an opening provided in the bushing 15' and depends therefrom to receive a collar 19 on the lower end thereof. A spider guide 24' is provided whereby the member 30 may be guided in its vertical movement as will hereinafter be explained. The collar 19 confines a valve seat 20 interiorly and between said collar and said length of tubing 18. A ball valve 21 is arranged to contact said seat for purposes hereinafter described and to provide for a quick positive action of the ball and seat valve a cross-pin 22 is provided a short distance above the ball whereby the upward travel thereof is limited.

25 A second elongated collar 23 is threaded to the collar 19 and depends therefrom and is provided with spider arms 24 at the extreme lower end thereof. A plurality of slots are provided in the wall of the collar for purposes hereinafter described. A valve head 26 being closed 30 by a spider 26' at its lower end is slidably confined within the collar 23 and is arranged to engage a seat 27 provided on the under side of the collar 19.

35 A valve stem 28 projects downwardly from the under side of the valve head 26 and is arranged to be secured in a leak-proof manner to the closed bottom 29 of a member 30, which functions as a float at such time as the fluid is displaced from the inside thereof. The extreme upper end of 40 the valve stem is provided with an integral auxiliary valve head 31 which valve head is arranged to engage a valve seat 32 provided internally in the top side of the valve head 26. The under side of the valve head 26 is closed and provided with an axial opening to permit reciproca-

tion of the valve stem 28 therethrough. This valve will be hereinafter referred to as the pilot valve. The purpose of this pilot valve is to provide a means for prohibiting the centering of the device in the event that a perfect vacuum would be formed both above and below the valve head 26. This pilot valve requires much less pressure to open than does the main valve.

In operation, after the device has been placed within the well in the desired position within the oil-bearing strata the fluid level within the well would be well above the ports 14 whereby the fluid may enter the housing 13 and pass downwardly thereof until such time as the housing is filled to the level equal that of the extreme upper end of the member 30. Continued gravity flow of the well fluid will fill the interior of this cup-like member 30 and finally force the air therein outwardly thereof. At this time the buoyancy of the member 30 is destroyed to allow the same to travel downwardly due to the gravity through the fluid within the housing 13.

Downward movement of the member 30 will cause the valve stem 28 and its integral valve head 31 to travel downwardly until such time as this enlarged head strikes the bottom spider 26' of the main valve head 26. The combined weight of the valve stem 28 and the member 30 will force the main valve head 26 downwardly to break the contact between this valve head and the seat 27 of the collar 19. At this time the usual pumping operation may be carried out. Attention is called to the fact that the ball and seat assembly 21 and 20 respectively serves to act as a second standing valve whereby the column of fluid is maintained at all times within the length of tubing 18 between the ball 21 and the regulation standing valve 10.

In the event that the fluid level within the well drops below the inlet ports 14, the pump (not shown) will remove the greater portion of the fluid within the member 30 to restore the buoyancy of the same to permit this member to "float" upwardly in the well fluid within the housing 13. Upward travel of this assembly will restore the parts to the positions shown in Figure 1 or the closed position.

In the event it is desired to flow a well with an auxiliary pressure this valve would operate in a like manner.

In Figure 4 a slightly modified form of the invention is shown and all identical parts bear like reference numerals.

In this form of the invention all parts are identical to those parts hereinbefore described. The difference being in inverting the member 30 whereby the closed portion 29 will be at the top while the open end is at the bottom. This member 30 is secured to the extreme lower end of the valve stem 28 in a manner similar to that form hereinbefore described. Guide spider arms 35 are provided internally of the housing 13 and are arranged to contact the outer periphery of the reciprocable member 30.

In the operation of this device, said device will be immersed in the well fluid a predetermined distance depending upon the depth of the bore hole, and the well fluid will enter the housing 13 through the inlet ports 14 in a manner similar to that hereinbefore described. As the weight of the fluid column within the housing 13 raises, this fluid will travel upwardly both in

the inverted member 30 and housing member 13. As the weight of the column within the housing increases the air trapped in the member 30 will be compressed by said column until such time as this air is compressed sufficiently to destroy the buoyancy of said member 30. As this occurs, the member through gravity will begin downward travel which, as has been explained, will open the pilot valve 31 and finally the main valve 26.

In the event that the well is pumped down to such a degree that fluid can no longer enter the housing 13, the pump (not shown) will pump the fluid from the upper portion of the housing 13 to reduce the column of fluid therein as well as the weight of said column. The compressed air within the inverted member 30 will expand as the weight of the column is decreased until such time as the main valve 26 and pilot valve 31 are again closed. The valve will remain closed until a sufficient weight of fluid is again imposed upon the member 30. In using an auxiliary pressure medium to flow the well the identical operation heretofore described would again take place to open the valve and at such time as this auxiliary pressure is diminished or the well pumped down the valve would close in the hereinbefore described manner.

From the foregoing it may be seen that a gas anchor or flow device may be had which device operates with equal efficiency whether the member 30 be open side up or open side down. Further, the device may be used either with the regular working barrel pump assembly or use a flow valve with auxiliary pressure.

Manifestly, the construction as shown and described is capable of some modification and such modification as may be construed within the scope and meaning of the appended claim is also considered to be within the spirit and intent of the invention.

What is claimed is:

In combination with a string of tubing and a standing valve in a well, a gas anchor including a tubular body disposed below the standing valve in said tubing string and provided with fluid inlet ports spaced below its upper end, a tubular member concentrically disposed in said body, a cylindrical member embracing said tubular member and reciprocable thereon, said cylindrical member having a closed lower end to render the same buoyant upon displacement of fluid therefrom, the movement of said cylindrical member being determined by influx of fluid through the ports in said tubular body, means interposed between said cylindrical member and tubular member for maintaining spaced relationship therebetween, a valve seat in said tubular member, a valve head cooperating with said valve seat and itself provided with a valve seat, a valve stem secured to said cylindrical member cooperating with the seat in said valve head and effective to maintain a pressure differential above and below said valve head, said valve head being displaceable to effect upward passage of well fluid through said tubular member standing valve and string of tubing when the buoyancy of said cylindrical member is destroyed, and means disposed above said valve head and seat to support the column of fluid subsequent to its passage by said first valve.

KORK KELLEY.
